J. F. COLLINS.
SWINGING SHELF FOR DESKS.
APPLICATION FILED MAR. 16, 1910.

981,979.

Patented Jan. 17, 1911.

UNITED STATES PATENT OFFICE.

JAMES F. COLLINS, OF WASHINGTON, DISTRICT OF COLUMBIA.

SWINGING SHELF FOR DESKS.

981,979.

Specification of Letters Patent. Patented Jan. 17, 1911.

Application filed March 16, 1910. Serial No. 549,770.

To all whom it may concern:

Be it known that I, JAMES F. COLLINS, a citizen of the United States of America, residing at Washington, in the District of Columbia, have invented certain new and useful Improvements in Swinging Shelves for Desks, &c., of which the following is a specification, reference being had therein to the accompanying drawing.

10 This invention relates to brackets especially adapted for use in connection with supporting rods of swinging shelves, and the principal object of the same is to provide a bracket that may be fastened to a corner portion of a desk, table or other articles of furniture to support a swinging shelf so that the latter may be swung to both sides of the corner to which it is connected.

15 The invention is particularly adapted for use in connection with shelves for typewriters, and provides means whereby a typewriter shelf may be pivotally connected to one corner of a desk so that the same may be swung to a position where the user may 20 operate the typewriter without leaving the desk, and when not in use, the shelf may be swung to one side of the desk so that it will not interfere with the customary use of the desk.

25 30 In carrying out the objects of the invention generally stated above it will be understood, of course, that the essential features thereof are necessarily susceptible of changes in details and structural arrangements, one preferred and practical embodiment of 35 which is shown in the accompanying drawings, wherein:

Figure 1 is a perspective view of a table desk showing a shelf pivotally connected thereto by the improved brackets. Fig. 2 is a fragmentary horizontal sectional view thereof dotted lines being used to indicate an adjusted position of the bracket. Fig. 3 is a perspective view of the improved 40 bracket. Fig. 4 is a similar view of the stationary member of the bracket. Fig. 5 is a vertical sectional view taken on the line 45 5—5, Fig. 3. Fig. 6 is a perspective view of a modified stationary member.

50 Referring to said accompanying drawings by numerals, it will be seen that the improved bracket comprises a flat plate 1 which is provided with openings 2 for the reception of fasteners, such as screws 3, by 55 means of which the bracket may be fastened in a horizontal position to one side of a

corner of a desk 4. At one end, said plate is provided with a flat pivot ear 5 which is arranged at right angles to said plate and having its free end projecting well beyond 60 the said plate and provided with an opening 6 that is preferably rectangular. The movable member of the bracket comprises a flat plate 7 having a pivot opening 8 in one end, and at its other end provided with a 65 socket 9 through which an opening 10 is formed. Said socket projects at right angles to plate 7 and is preferably in the form of a pendent tube.

A bolt is employed for holding the stationary member and the movable member of the bracket in pivotal engagement, said bolt having an enlarged head 11, a squared neck 12 and a threaded cylindrical shank 13. The squared neck 12 of said bolt is fitted within 70 the squared opening of pivot ear 5 so that rotation of said bolt relative to said ear is prevented. The shank 13 fits loosely within the end opening of plate 7 so that pivotal movement of said plate is permitted. A 75 washer 14 is interposed between the head of the pivot bolt and ear 5, and a lock nut 15 and interposed washer 16 are carried by the threaded shank of said bolt for holding the stationary member and the movable member 80 of the bracket in pivotal relation.

In use, as is suggested in Fig. 1, two of the improved brackets are employed for supporting a shelf, one being at the upper portion and the other at the lower portion of a 90 desk, and the sockets 9 of said brackets receive the ends of a shelf post 17. Said post carries a lower-adjustable collar 18 from which arms 19 project which are suitably fastened to a shelf 20. Said shelf is connected at one corner to a collar 21 also adjustably mounted on post 17. It is preferred to form the socket opening of the 95 upper bracket in cylindrical shape, and the socket opening of the lower bracket in rectangular shape, which obviously facilitates the positioning or removal of post 17. A set screw 22 is carried by the socket of the lower bracket for locking the post 17 to said 100 socket.

105 It will be seen from the foregoing that the improved brackets permit the shelf to be readily swung around the corner of a desk so that the occupant thereof will have 110 access to said shelf, as is shown in full lines in Fig. 1, and when access to the shelf is not desired, the same may be swung to the dot-

ted line position indicated in said figure so that it will not interfere with the use of the desk. It will also be understood, that the plate and pivot ear of the stationary members are preferably integral, and the plate and socket of the movable members are also preferably integral, and may be cast thus providing a bracket which may be manufactured at the minimum of cost and without requiring skilled labor.

In the modified form of the invention shown in Fig. 6, the plate 23 of the movable member is adapted to be placed in a vertical position on a desk and the pivot ear 24 thereof projects at right angles from the longitudinal center thereof. Said plate and ear are preferably integral.

What I claim as my invention is:—

As a new article of manufacture, a bracket 20 of the class described, comprising a flat apertured plate provided only at one end with an integral, horizontal ear, said ear projecting beyond the end and being provided with a squared, vertical aperture near 25 its outer end, a flat, swinging-plate in engagement with one of the horizontal faces of

the ear and provided with a round aperture registering with the square aperture, a fastening-member provided with a square portion, the square portion seated in the square aperture of the ear, said fastening member provided with a round portion positioned in the round aperture of the swinging-plate, means on said fastening member for retaining the swinging-member 30 in engagement with the ear, permitting the same to swing in a horizontal plane, said swinging-member provided at its outer end with an enlarged, depending hub-like portion, said hub-like portion being provided 35 with a square post or standard-receiving opening or socket, and clamping means extending into the square socket and carried by the hub-like portion, substantially as shown and described.

In testimony whereof I hereunto affix my signature in presence of two witnesses.

JAMES F. COLLINS.
